UNITED STATES PATENT OFFICE

WILLIAM J. ASHER, OF COLORADO SPRINGS, COLORADO

IRONING MACHINE

Application filed July 8, 1926. Serial No. 121,220.

The present invention relates to power operated ironing machines.

In the modern power laundry, it is necessary to handle not only flat articles varying in size and thickness, such as sheets, blankets and handkerchiefs, but it is also necessary to handle all types of garments which not only vary in size, shape and thickness but which often are provided with buttons which should not be broken by the laundry machinery. While satisfactory washing and drying machines entirely capable of cleaning and drying all classes of wearing apparel and household goods have been devised, the problem of ironing satisfactorily and without wrinkling all classes and description of household linen and garments has as yet not been entirely solved, altho many attempts have been made to provide large capacity power driven ironing machines or mangles, which meet all requirements of the trade. It will be understood that the articles should preferably be ironed upon both sides, should not be wrinkled in passing thru the ironing machine, should not be subjected to excessive tension and that the buttons should not be broken or torn off during the ironing operation. It is a further and important consideration to provide a large capacity machine which occupies a minimum of floor space since the power laundries are, in general, located in the larger cities where the floor space for the various units is limited.

The present invention provides an ironing machine which meets all requirements. It is so designed and constructed as to be able to handle all types of "flat work" from the largest, such as sheets and blankets to the smallest, such as handkerchiefs of delicate character, ironing each article on both sides and delivering it in a smooth and unwrinkled condition. It furthermore is capable of satisfactorily ironing all types of body garments, whatever the texture of the cloth or thickness and regardless of the presence of buttons, without damaging such articles. Furthermore my improved ironing machine has a very large capacity for the floor space which it occupies, thus making it a convenient one to install where floor space is at a premium.

It has many features of novelty which will be apparent to one skilled in the art from a reading of the following specification and an inspection of the accompanying drawings and these features will, of course, be particularly pointed out in the claims.

In the drawings:

Figure 1 is a side elevation of the machine;

Figure 2 is a plan view of the same;

Figures 3 to 13 illustrate the mechanism for controlling the pressure rollers, Figure 3 being a longitudinal section thru the machine showing the pressure rollers and their operating mechanism together with the cylinders and aprons but omitting the rest of the apparatus;

Figure 4 is a view of a portion of the mechanism shown in Figure 3, the parts however being shown in different positions to illustrate its mode of operation;

Figure 5 is the transverse section thru the axle of the first cylinder, showing one of the pressure rollers and its adjusting mechanism;

Figure 6 is a section on line 6-6 of Figure 5;

Figure 7 is a section on line 7-7 of Figure 5;

Figure 8 is a section on line 8-8 of Figure 5.

Figure 9 is a section thru a portion of the mechanism for operating the pressure rollers.

Figure 10 is an elevation of a portion of the power operated pressure roller adjusting mechanism;

Figure 11 is a plan view of a detail;

Figure 12 is a plan view of the mechanism illustrated in Figure 10;

Figure 13 is a section on line 13-13 of Figure 12;

Figure 14 is an elevation, broken away in part, of the power throw-off and starting mechanism;

Figure 14^a is a section on line 14^a-14^a of Figure 14;

Figure 15 is a section on line 15-15 of Figure 14;

Figure 16 is a side elevation of the driving pulley and clutch mechanism shown in Figure 14;

- Figure 17 is a section on line 17—17 of Figure 14;
- Figure 18 is a plan view of a detail;
- Figure 19 is a section of a detail;
- 5 Figure 20 is a section on line 20—20 of Figure 19;
- Figure 21 is a section on line 21—21 of Figure 14;
- 10 Figure 22 is a section on line 22—22 of Figure 14;
- Figure 23 is a longitudinal section thru a portion of the machine showing the mechanism for adjusting an apron guide roller and tape guide roller associated with the first 15 cylinder;
- 15 Figure 24 is a plan view of this mechanism;
- Figure 25 is a side elevation of a portion of the machine showing details of the mechanism for maintaining predetermined tension in the aprons;
- 20 Figure 26 is a top plan view of the same;
- Figure 27 is a section on line 27—27 of Figure 26;
- 25 Figures 28 and 29 illustrate in side elevation and in different positions respectively one of the features of the apron tensioning mechanism;
- 30 Figure 30 is a plan view of the same, partly broken away;
- 30 Figure 30^a is an elevation of portion of the mechanism shown in Figures 25, 26 and 27;
- Figure 31 is a section on line 31—31 of Figure 32;
- 35 Figure 32 shows in elevation, partly broken away, the adjusting means for one of the apron rollers and by means of which the roller may be tilted;
- 40 Figure 33 is a section thru the tape supporting and tension adjusting mechanism associated with the first cylinder;
- Figure 34 is a section on line 34—34 of Figure 33;
- 45 Figure 35 is a section on line 35—35 of Figure 33;
- 50 Figure 36 is a side view of one of the adjustable gear trains for driving the pressure and tape supporting rollers of the first cylinder, together with the adjustable gear guard which is associated therewith;
- 55 Figure 37 is a side elevation of a second form of adjustable gear guard; and
- Figure 38 is a plan view of a roller of non-uniform surface for loosening the articles ironed by the first cylinder from the belt associated therewith.
- 60 The general shape of the machine will be realized from an inspection of Figures 1 and 2 of the drawings and from these views it is apparent that all of the operating parts are mounted in the parallel side walls 10 and 11 of a large frame, the frame having a bottom portion 12 which may be mounted upon a substantial base. Preferably it is mounted upon a concrete block since the machines are 65 usually of large size, say fifteen feet long by
- twelve feet wide by seven feet high. There is little vibration due to the operation of the machine inasmuch as all of the larger operating parts merely rotate about fixed axes but, at the same time, it is advantageous to anchor the base as firmly as possible. The side members 10 and 11 of the frame have numerous openings some of which are provided for the reception of bearings for shafts, etc., and others of which are merely provided to lessen the weight of the frame and reduce the expense of manufacture. Two of these openings are indicated at 13 and 14 respectively in Figure 1 and it will be understood that corresponding openings are provided in the opposite side 10 of the frame. Supported upon the lower edges of these four openings are four bearings each of which is indicated generally at B. The opposed bearings of each pair are in axial alignment and receive the cylindrical axial projections 15 of the cylinders 16 and 17. These cylinders 16 and 17 are heated by steam or other heating agent in any well known manner and constitute the ironing cylinders, the cylindrical faces of the cylinders constituting ironing surfaces for the goods which pass thru the machine. They are driven in opposite directions from a constantly operating source and at slightly different speeds. Thus the drive gearing is so arranged that in the actual operation of the machine the cylinder 16 is driven faster than the cylinder 17.
- The drive pulley for both cylinders is indicated at 18 and this pulley may be driven by any suitable source of power, as for instance an apron, an electric motor or other appliance. By means of a clutch mechanism indicated generally at C the pulley may be operatively engaged with, or disengaged from, the drive shaft 19 of the machine. Upon this drive shaft 19 is rigidly secured a pinion 20 which meshes with a gear wheel 21 fixed upon an idler shaft 22. The teeth of gear 21 mesh with those of a second gear 23 mounted upon an idler shaft 24. Idler shafts 22 and 24 carry pinions 25 and 26 respectively, which pinions are in engagement with large gears 27 and 28 which are fixed upon the axles of the heated cylinders. From this arrangement of gearing it follows that the cylinders are driven in opposite directions and at substantially the same speed but it will also be observed that the gear wheel 21 is of slightly less diameter than gear wheel 23 and, since the pinions 25 and 26 are the same in size, this results in the cylinder 16 being driven at a somewhat faster rate of speed than cylinder 17.
- By means of the clutch mechanism indicated generally at C the driving power may be applied or thrown off at the will of the operator and this clutch is so designed that the mechanical shock due to starting the ma- 130

chine from a constantly operating power member is reduced to a minimum. The details of the clutch are shown in Figures 14, 15 and 16. The driving pulley 18 has a 5 sleeve-like hub member 30 which is freely rotatable upon shaft 19 which shaft is supported in the frame, one end being journaled in a side frame member and the end shown in Figure 15 being supported from the frame 10 by brackets 32. Keyed to shaft 19 is a hub 33 having a cylindrical outer surface and having at its outer end spaced parallel substantially tangentially extending members 34. The outer ends of these members 34 constitute 15 supports for friction shoes 35 the cylindrical surfaces of which are adapted to bear against the inner cylindrical friction surface of pulley 18. The connection between the friction shoes 35 and members 34 is such that the friction shoes may be 20 adjusted radially to shaft 19 by mechanism now to be described in order to make or break frictional engagement between the pulley and shaft 19. Preferably bolts 36 rigid with 25 the friction shoes slidably extend within apertures in the outer ends of members 34, as shown in Figure 14, but other connections of this character may be provided if desired which permit the friction shoes to be radially 30 adjustable yet maintaining them against movement circumferentially of the shaft 19.

The central portion of each friction shoe 35 is connected by an adjustable link 37 to a sleeve 38 slidably mounted upon the cylindrical outer surface of hub 33. This sleeve is provided with an external groove 39 which receives inwardly projecting pins 40 of a yoke member 41 mounted on the upper end of a lever 42 pivoted at 43 (Figure 16) to 40 a bracket 44 fastened to the frame. By means of lever 42 sleeve 38 may be moved axially of shaft 19 and the friction shoes thrust against, or withdrawn from contact with, the constantly running pulley 18. 45 With the friction shoes in engagement with the pulley, power is taken therefrom and transferred thru members 34 to hub 33 and thence to the shaft 19. The power is not suddenly applied since the friction shoes will 50 be thrust outwardly rather slowly by the links to make a gradual frictional engagement with the pulley. This is of the greatest importance in a power throw-off for a machine of the character under consideration 55 and having a considerable number of operating parts of large size and opposing a starting movement with large inertia forces.

The lower end of lever 42 is connected by 60 a link 45 to one end of a crank 46 mounted upon the end of a rotatable shaft or control element 47. This shaft or control element is rotatable thru an angle of 90°, its rotation thru this angle being limited by the fixed 65 stops 47¹ and 47² between which the crank

oscillates. Rotation of this shaft in a clockwise direction causes engagement of the friction shoes 35 with the pulley and starting of the machine, and rotation of the shaft in the opposite direction causes disengagement of the 70 shoes from the pulley and stopping of the machine. Several independently operative devices are provided for bringing about movement of the control element or shaft 47. Thus this shaft may be operated by an automatic stop mechanism which is brought into action when the hand of the operator, who is engaged in feeding articles into the machine, becomes endangered by moving too far toward the point of introduction of the articles 75 into the machine, or it may be operated by a mechanism in the nature of a hand lever or foot treadle which is entirely under the control of the operator. Again, shaft 47 may be operated by a control lever which is moved 80 by the operator to effect starting of the machine after the automatic means has functioned to stop the machine. These three operating devices are illustrated in Figures 14, 17, 18, 19, 20, 21 and 22 and the details of this 85 device will now be explained.

The control shaft 47 extends forwardly from the friction clutch mechanism C to the proximity of the front of the machine where the feeding of the articles to the first cylinder is done. The forward end of this shaft extends thru a bearing in a bracket 50 supported on the frame, this bracket providing two spaced bearings for the shaft that is, a bearing at 51 for the forward end of the shaft 100 and a bearing at 52 for an intermediate portion. Intermediate these bearings the shaft is provided with a bevel gear 53 and a small bevel pinion 54. Pinion 54 is fixed on the shaft but bevel wheel 53 is mounted upon a 105 sleeve 55 which is rotatable relatively to the shaft this sleeve having a slot 56 formed therein thru which a pin 57 projecting radially from the shaft, extends, the length of slot 56 being approximately 90°, as shown in Figure 21, so that shaft 47 may rotate thru a quarter revolution from the position in which it is illustrated in the drawings, to effect the throwing off of the power by disengagement of the friction shoes from the pulley, without causing rotation of bevel wheel 53. The teeth of bevel wheel 53 mesh with those of a bevel pinion 58 rigidly mounted upon the lower end of a rotatable shaft 59. This shaft is disposed substantially vertically, its lower end passing thru a bearing 60 forming a part of bracket 50 and its upper end passing thru a bearing 61 bolted to the frame, as shown in Figure 19. The upper portion of shaft 59 projects above the frame 125 and upon its upper end is axially mounted a disk 62 having cam 63 rigid therewith. This cam is shown in plan in Figure 18 and is seen to be semicircular with a peak at 64. Against the side of the peak of cam 63 lies a finger 130

65 which extends thru and is supported by a rotatable shaft 66. Also mounted upon shaft 66, which extends transversely of the machine and from side to side thereof, are spaced 5 arms 67 which carry respectively the ends of roller 68. This roller directly overlies the feed board 69 of the machine and bears downwardly upon the articles which are passed over this feed board toward the first cylinder.

- 10 In the event that the hand of the operator accidentally passes too far toward the first cylinder it will pass under and elevate the roller 68, lifting finger 65 at the same time and thus disengaging this finger from the side 15 64 of cam 63. Immediately upon such disengagement a coil spring 70 becomes active to rotate shaft 59 in the direction of the arrow X, which results in immediate rotation of the control element 47 in the direction of the arrow Y, and stopping of the machine.

The spring 70 has its upper end permanently connected to the under side of the disk 62 and its lower end permanently connected to the bearing 61. This latter bearing is rotatable, when its securing bolts 71 are loosened, by inserting short levers into apertures 72 provided for that purpose, in order that the spring tension may be adjusted to suit operating conditions. The machine having been 30 stopped it can again be started only by actuation of the starting lever 73. The upper end of this lever is provided with a handle portion by means of which it may be easily grasped by the operator and its lower end is 35 provided with an integral sleeve-like portion 74 which is rotatably mounted upon a shaft 75 extending transversely of and rotatably mounted in the frame. One face of the sleeve 74 is provided with a projection or tooth 76 40 which extends within a slot 77 of a sleeve 78 non-rotatably secured to shaft 75. Also fixed on this shaft is a bevel wheel 79 the teeth of 45 which engage with those of the bevel pinion 54 previously mentioned, from which it can be seen that rotation of the shaft 75 in the 50 direction of arrow Z (Figure 22), will cause rotation of control shaft 47 in the direction of arrow Y (Figure 14), and hence stopping of the machine. Shaft 75 is normally held in 55 the position in which it is shown in the drawings, i. e., so that the clutch is engaged, by a force developed by the influence of gravity upon the weight 80 adjustably mounted upon the outer end of an arm 81 projecting radially 55 from a sleeve 82 fixed on shaft 75.

A treadle bar is illustrated at 83 and the ends of this bar are supported upon rods 84 projecting radially from sleeves 85 rotatably mounted on shaft 75. Only one of these 60 sleeves is shown but it is understood that they are identical in construction. Sleeve 85 has a tooth 86 which projects into a recess or slot 87 in cylindrical block 88 rigidly fastened upon shaft 75. The weight of the treadle 83 65 is in large part counterbalanced by a weight

89 adjustably supported upon a rod 90 rigid with the sleeve 85. The treadle, however, overbalances the weight so that the tooth 86 is normally in engagement with the left hand end of the slot 87, as seen in Figure 22. A 70 collar 91 prevents lateral movement of the sleeve 85 on the shaft.

The action of the automatic stop mechanism has previously been explained. From the description just given, however, it will be 75 apparent that when the control shaft 47 is moved by the automatic mechanism to stop the machine the shaft 75 will be at the same time rotated, thru the influence of the intermeshing gears 79 and 54, in the direction of 80 the arrow Z. Since both the starting lever 73 and the foot treadle 84 have "lost motion" connections with the shaft 75 these members will not be actuated when the automatic stop functions but will remain stationary, the 85 movements of the blocks 78 and 88, however, bringing the teeth 76 and 86 into engagement with the opposite ends of the slots 77 and 87. During the rotation of shaft 75 lever 73 is 90 prevented from falling by engagement with the stop 92, while the treadle maintains substantially the position in which it is shown in Figure 14, the weight 89 resting on the floor or a suitable base or support. With the machine stopped and the tooth 76 in engagement 95 with the right hand end of slot 77 (Figure 22) it is only necessary, to start the machine, to move the hand lever 73 in the direction of the arrow W (Figure 14). This not only results in reestablishment of the power connection to the constantly running pulley but also 100 effects resetting of the automatic throw-off mechanism, the shaft 59 being rotated during such movement of the lever 73 in a direction contrary to that indicated by the arrow 105 X thru three quarters of a revolution, the finger 65 riding up the face of cam 64 and falling over the peak of the cam to take the position in which it is shown in Figures 14 and 18.

Normally of course, the machine is stopped and started by means of the treadle which is within convenient reach of the operator's foot. Pressure on this treadle effects rotation of the control shaft 47 but, because of the 115 lost motion connections between shafts 75 and hand lever 73, and between shaft 47 and bevel gear 53, neither the hand lever nor the automatic stop mechanism is operated as a result of the manipulation of the treadle. The arrangement of stopping and starting devices just described is of the greatest practical importance. The machine is easily and conveniently controlled from the point of feeding, where the operator is positioned and the various control instrumentalities are connected to the power throw-off mechanism with a minimum number of operating parts. These parts are of simple nature, easily inspected, cleaned and kept in repair and are of type considered 120 125 130

ideal for laundry machine purposes. In connection with the automatic throw-off mechanism two auxiliary handles 93, 93 may be provided whereby the operator can effect the 5 speedy stoppage of the machine manually, even tho it is impossible to reach the treadle 83. These levers 93 are connected respectively to the lower ends of the swinging supports 67 for the roller 68. To effect a quick 10 stoppage it is only necessary for the operator to press downwardly on either one of the levers 93 which results in upward swinging of supports 67 and release of cam 63 by finger 65. There may be only one of these levers 15 93 if two are considered unnecessary.

Associated with each of the cylinders is an endless apron. The apron of the first cylinder is indicated at 100 and that of the second cylinder at 101. These aprons are guided 20 over rollers hereinafter to be fully described and are employed for the purpose of holding the articles being ironed in close contact with the cylinders as the cylinders revolve about their axes. The aprons further cooperate in 25 transferring the goods, ironed on one side by the first cylinder, to the second cylinder where the articles are ironed on the opposite side. The aprons may be made of various materials, as is well known but with the ar- 30 rangement of pressure and guide rollers which I employ in the present machine the relatively inexpensive cotton aprons may be employed with very satisfactory results. The arrangement of aprons is most clearly illus- 35 trated in Figure 3. Here the end of the feed board is indicated at 102 and this end is shown to be positioned in close proximity to the first pressure roller 103 associated with cylinder 17.

40 The apron 100 passes around pressure roller 103 moving in the direction indicated by the arrow and articles passing from the feed board on to the top of pressure roller 103 are drawn downwardly between the 45 apron 100 and the outer cylindrical ironing surface of cylinder 17. This cylinder is in constant rotation and the endless apron 100 constantly passes on to the same at one point, i. e., between pressure roller 103 and the cyl- 50 inder, and is constantly removed at another point, i. e., adjacent the apron drive roll 104. Very nearly the entire surface of the cylinder, therefore, is covered by the apron and the goods being ironed are tightly pressed there- 55 by, during the period of their travel around the cylinder axis, against the cylinder. In addition to pressure roller 103 additional pres- 60 sure rollers are provided indicated respec- tively at 105, 106 and 107, the function of 65 these rollers being solely to press the apron tightly against the cylinder. The rollers are therefore provided with layers of relatively soft materials on their surfaces, such as rubber or cloth.

65 The degree of pressure with which the

rollers bear on the apron may be varied, by means hereinafter to be described, or the rollers may be retracted from the cylinder so as to permit the apron to separate itself from, or to lie loosely against, the cylinder 70 to prevent overheating and burning of the apron when the machine is not in operation. After the articles being ironed have passed around the cylinder 17 from pressure roller 103 to the proximity of the drive roller 104 75 they are removed from the ironing surface by the doffing knives 108 mounted upon the transversely extending doffing bar 109. They are next conveyed over and to the rear of cylinder 17 by the apron 100 and its co- 80 operating tapes 110, clearly shown in Figures 2 and 3. The articles are transported over guide rollers 104' and delivered by the apron 100 to a point adjacent the guide roller 111 positioned intermediate the two cylinders 85 and at this point are for the first time also engaged by the second apron 101 which likewise passes over roller 111. Thus held between the two aprons the articles being handled pass downwardly, around the apron 90 tensioning roller 112, under the pressure rollers 113, 114 and 115 of the second cylinder to the point 116 where the aprons separate, the first apron passing over the rollers 117, 118 and 119 and returning to the first cylinder 95 in the direction of the arrow and the second apron passing around roller 115 on to the surface of the cylinder 16.

Between the rollers 111 and 112 the aprons may have a tendency to separate and allow 100 the articles carried therebetween to become displaced or wrinkled. To prevent such separation, I provide a pressure roller 100' which is supported on an arm 100', mounted to swing about a shaft 100'. Rigid with this 105 arm is a weight 100'', the action of which is to increase the natural pressure of the roller. The arrangement is such that, if the aprons stretch and the roller approaches a position vertically below its point of suspension so 110 that its pressure is decreased, the lever arm of the weight is increased and the pressure of the roller against the apron maintained.

After passing around the cylinder the second apron passes over the apron drive 115 roller 120, guide roller 121, adjusting and driving roll 122 and guide roll 123, thence downwardly over the common guide roll 111. The articles, after being ironed by both cylinders are removed from the surface of the 120 second cylinder by doffing knives indicated at 124 and discharged on to the surface of a folding board.

As it is desirable to vary the pressure of 125 the rollers against the aprons for different classes of articles being handled, as previously pointed out, means is provided by which such adjustment may be quickly and easily carried out by the operator. Each of the pressure rollers 103, 105, 106, 107, 113, 114 130

and 115 is rotatably mounted upon an axle and the ends of each axle are mounted on links 125, the links of the several rollers being identical in character. Each link has one end pivotally supported on the frame as at 126 and its opposite end connected by means of a rod, indicated generally at R, to a rotatable member mounted on the corresponding cylinder axle. The links and rods are identical on the two sides of the machine and hence those at one side only will be described. The rotatable member to which the rods R of the left hand group of pressure rollers (Figure 3) are connected is indicated at 127 and the corresponding rotatable member of the right hand group of pressure rollers at 128. From Figures 5, 6 and 7 the construction of the rods R (all of which are identical in construction) and the rotatable member 127, can be observed.

Member 127 is seen to be an annular sleeve-like member rotatably mounted upon an annular extension 127' of the bearing for the axle of cylinder 17. It is provided with grooves 129 for the reception of the inner ends of rods R and has, at one side, a radial projection 130 which constitutes a lever arm by means of which it may be rotated.

The rods R are extensible, each of these rods having two telescoping portions, a tubular outer portion 131 and an inner portion 132 slidably fitting within the same. Movement of portion 132 into tube 131 is limited by nuts 132' adjustably positioned on rod 132. The tubular portion 131 is slotted at 133 and a pin 134 extending thru this slot establishes a connection between the end of the inner portion 132 of the rod and a sliding abutment 135 mounted upon the outer member. A spring 136, normally in compression, has one end resting against abutment 135 and the other end against the innermost of a pair of adjusting nuts 136' threaded on tube 131. The arrangement is such that the spring normally tends to shorten the rod by forcing the abutment 135 away from the abutment 136', that is by drawing the solid portion of the rod within the tubular portion. As a result the pressure rollers are, in the normal operation of the machine, drawn against the aprons and cylinders by the action of these springs. The action of each individual spring may be adjusted by means of the adjusting nuts 136' so that by making suitable adjustments the several pressure rollers may be caused to bear against the cylinder with the same amount of force.

Rotation of the annular member 127 in a counter-clockwise direction (Figure 3) of course results in lengthening of rods R and hence in increasing the tension in the springs so that the pressure rollers are drawn against the cylinder with increased pressure and rotation of this member in the opposite direction results in decreased tension in the springs and

results in lessened pressure of the rollers against the cylinder. Continued movement of member 127 in this direction results in nuts 132' of rods R striking the ends of tubular portions 131 so that the rods may deliver a thrust if called upon to do so.

The same is true with respect to the group of pressure rollers and extensible rods associated with the cylinder 16. Rotation of an annular member 128 in one direction increases the spring tension and rotation in the opposite direction decreases the spring tension. The operating lever 140 connected to the annular member 128 is, however, a double arm lever, instead of a single arm lever as is clear from an inspection of Figure 3. The means for operating the levers 130 and 140 to effect changes in pressure of the pressure rollers against the cylinders will now be described.

Arm 130 has a pin and slot connection with a link 141 and the upper arm of double arm lever 140 has a pin and slot connection with a link 142, the opposite ends of these links being pivotally connected to the extremities of a lever 143, clearly shown in Figures 3 and 9. Lever 143 is fixed upon a rotatable shaft 144 and by rotating this shaft the lever may be revolved from the position in which it is shown in Figures 3 and 9 to the position in which it is shown in full lines in Figure 4. Rotation of this lever thru 180° as shown effects longitudinal movement of the links 141 and 142 and causes these links to move the levers 130 and 140 to the positions in which they are shown in Figure 4. Annular members 127 and 128 are of course given the same angular movement as levers 130 and 140 and as a result of this movement the effective lengths of the rods R of both cylinders are decreased, the tension of springs 136 decreased and the rollers are drawn toward the cylinders with considerably less pressure than before. The two adjustments just described represent the extreme adjustments which may be made to vary the spring pressure in the ordinary operation of the machine. With the parts adjusted as shown in Figure 3 the rollers are drawn toward the cylinders with the maximum pressure desired, and this pressure may be employed when flat work is passing thru the machine. When garments having buttons are being ironed the double arm lever 143 is turned to the position shown in Figure 4 and the pressure of the springs 136 is materially less so that the buttons passing thru will not be broken. The means for rotating shaft 144 to effect movement of double arm lever 143 will be hereinafter described.

When operation of the machine is discontinued, for instance in the evening after the day's run, it is desirable that the rollers be withdrawn from the cylinders a short distance thereby allowing the aprons to fall away from the heated but stationary surfaces of the cylinders to prevent their overheating.

or burning. The mechanism so far described only provides for regulating the pressure with which the rollers are pressed against the cylinders. This mechanism may be operated 5 from time to time during the day, or much more frequently than the mechanism for disengaging the pressure rollers from the cylinders and hence the machine is designed so that the first mentioned mechanism may be 10 operated readily without necessitating the manipulation of the second.

From Figures 3 and 4 it will be seen that levers 130 and 140 have pin and slot connections respectively with additional link members, indicated at 148 and 149. The inner ends of these links are pivotally connected to a crank arm 150 rotatably mounted on a stub shaft 151 and provided with an operating handle 152. The slots in the ends of links 20 148 and 149 are relatively long and, during the rotation of levers 130 and 140 due to the manipulation of the double arm lever 143 the pins of these levers merely move idly in the slots of links 148 and 149, until the pins just 25 referred to, which are indicated at 153 and 154 respectively, reach the ends of the slots, which slots may be designated 155 and 156. As a matter of fact, the rotation of members 127 and 128 is brought about wholly by the 30 action of springs 136 and not by thrusting action of links 141 and 142 and the expansion of these springs, and rotation of members 127 and 128 is only terminated when pins 153 and 35 154 reach the ends of the slots in which they are moving, the links 148 and 149 serving, at this point, as abutments or as limiting members preventing the pressure of the rollers from being decreased below a certain amount. In order that the pressure rollers may move 40 away from the cylinders, therefore, it is necessary to operate links 148 and 149 in such manner that they are no longer effective as stops. This is brought about by movement 45 of the lever 150 which is moved by the operator from the position in which it is shown in full lines in Figures 3 and 4 to the position in which it is shown in dotted lines in Figure 4. As a result of such movement the levers 130 and 140 with the annular members 50 127 and 128 respectively are free to rotate further and this they readily do under the pull of the rods R, which by this time have ceased to contract, and are drawn outwardly by the weight of the pressure rollers. It will 55 be seen that six of the pressure rollers will fall away from their respective cylinders under the influence of gravity alone while a single one only needs to be lifted, i. e., pressure roller 107. Rollers 103, 105 and 106, however, 60 exert a sufficient turning moment on annular member 127 to cause the rod R associated with roller 107, which rod has been fully telescoped in the manner previously explained, to thrust that roller away from the cylinder. 65

By simple movement of the crank 150,

therefore, all of the pressure rollers are freed and drop back a quarter or one-half inch so that the aprons are no longer pressed against the heated cylinder surfaces. This adjustment of the parts will be maintained until the 70 lever 143 is again operated to cause the pressure rollers to be drawn toward the cylinders, that is, into the position in which they are drawn with maximum spring pressure 75 against the cylinder surfaces by the springs 136. The lever 150 may then be returned to its full line position, the links 148 and 149 again acting as stops limiting the movements of levers 130 and 140, in adjusting the rollers to flat or button work positions, as previously 80 set forth.

Inasmuch as the pressure of the pressure rollers may be adjusted a number of times during a day's operation of the machine I have found it desirable to operate this mechanism by power instead of manually in order that the operator may be spared as much manual effort as possible. This mechanism is shown in Figures 3 and 9 to 13, inclusive. The shaft 144 upon which the double arm 90 lever 143 is rigidly mounted is seen to extend transversely across the machine and to have its ends rotatably supported in the sides of the frame. Upon this shaft is slidably mounted a block 160, this block being splined 95 to the shaft so as to be rotatable therewith and having two toothed segments 161 and 162 respectively integral therewith. By sliding block 160 in one direction on shaft 144, segment 161 may be brought into mesh with 100 a pinion 163 and by sliding the block in the opposite direction, segment 162 may be brought into mesh with gear 26. Pinion 163 is in mesh with gear 26 and the teeth of gear 26 in turn mesh with those of the large power 105 drive gear 28. While the machine is operating gear 26 and pinion 163 are constantly rotated, altho in opposite directions. By sliding block 160, therefore, either segment 110 161 or 162 may be meshed with the corresponding gear and the shaft 144 rotated in either direction. The extent of such rotation is limited by the length of the segments 161 and 162, rotation continuing until the segment then in mesh with its corresponding gear has run past the gear disengaging the 115 same.

The fingers 166 of a yoke on the end of an arm 167 rigidly mounted upon a sliding shaft 120 168 extend into a groove 169 formed in a spindle-like projection from the end of block 160. Shaft 168 has its ends slidably mounted in bearings 170 and 171 formed respectively in the frame, and in bracket 172. Bracket 172 is bolted to the frame and not only provides a bearing for one end of shaft 168 but forms a support for the outer end of the stub shaft 24 upon which the gear 26 is rotatably mounted. At its outer end shaft 125 168 is provided with a slot 174 which receives 130

a pin 175 projecting from the outer end of an arm 176 fastened on the end of a crank shaft 177. This crank shaft extends longitudinally of the machine, as can be seen from Figure 3 and is provided at its outer end with an operating handle 178. The operator positioned at the end of the machine may, therefore, by rotating shaft 177 by means of the handle 178, slide shaft 168 in either direction and hence effect rocking of shaft 144 and adjustment of the pressure rollers as desired, by power taken from the power driven mechanism of the machine, rather than by manual exertion.

15 A feature of the invention which constitutes a decided improvement over prior ironing machines of the endless apron type is illustrated in detail in Figures 23 and 24. The apron drive roll 104 has its ends rotatably supported in arms 180 of a frame indicated generally at F. This frame is tiltable, the inner ends of arms 180 being keyed on a rock shaft 181 mounted in the main frame. The end of shaft 181 carries a worm wheel 182 the teeth of which mesh with those of a worm 183 on a shaft 184 provided with an operating hand wheel 185. Rotation of the hand wheel results therefore in rotation of shaft 181 and varying of the angular position of 20 the arms 180 of the frame F. Tape driving rollers 186 and 187 also have their ends rotatably supported in the tilting frame F, these rollers receiving between them the parallel tapes which co-operate with the first 25 apron in transferring the articles just removed from the first cylinder by the doffing bar, to the second cylinder. Rolls 104 and 186 are driving rollers, the shafts of these rollers being provided respectively with 30 gears indicated at 188 and 189, the teeth of these gears intermeshing so that the two tape driving rollers are driven from the apron roller gear 188, roller 186 being positively driven and roller 187 driven thru frictional 35 contact therewith. A second gear 191 is mounted on the shaft of the apron roller 104 being rotatable with this shaft and with gear 188, and this second gear is in mesh with a gear 192 rotatably mounted on shaft 181 40 and driven by power derived from the main gear 28 which power is transmitted thereto thru a sleeve-like member 193 rotatably mounted on a stub shaft 194 projecting laterally from the frame sleeve 193 having teeth 45 195 at one end meshing with the teeth of main gear 28 and a gear 196 at the other end meshing with gear 192. The arrangement is such that the frame F may be raised and lowered 50 without unmeshing and remeshing the gears, that is, without destroying the driving connection thru the gearing just mentioned, the gear 192 being at all times coaxial with the axis of rotation of the frame F and the gear 191 moving circumferentially around this axis.

55 60 65 66 A ready means for lifting the frame and

its associated rollers for the purpose of inspecting the doffing bar and for loosening the apron at the end of a day's run, is thus provided, without breaking the driving connection to the gears. It should further be noted that by means of the worm and worm wheel adjusting devices the frame is locked in any desired position of adjustment.

The cotton or other aprons used with the ironing machine gradually lengthen during the period of their useful life and it is customary therefore, to provide an automatic apron tensioning device by means of which slack which occurs can be taken up. The improved apron tensioning device which I have developed is illustrated in Figures 25 to 30^a, inclusive. Both aprons pass around roller 112 and this roller is shown to be rotatably mounted upon a shaft 200 extending transversely of the machine, one end of the shaft protruding thru an elongated substantially horizontal aperture 201 formed in one of the side frame members. Fixed on the shaft are spaced pinions 202, the teeth of which mesh with those of spaced parallel racks 203 which racks are supported from the sides of the frame by brackets 204. Fixed on the outer end of shaft 200 is a gear 205.

The rotation of shaft 200 results in movement thereof longitudinally of the machine, carrying roller 112 with it, the pinions 202 "walking" on racks 203. Guide bars 206 and 207 extend longitudinally of the frame, the lower edges of these guide bars being parallel to the supporting racks 203 and being so positioned relatively to the shaft 200 as to prevent lifting of the shaft out of contact with the racks. Also fixed on shaft 200 and positioned on opposite sides of guide bar 206 are collars 208, these collars being provided to prevent axial movement of shaft 200. Rotatably supported on shaft 200 intermediate the pinion 202 and gear 205 is a substantially cylindrical member comprising two hubs 209 and 210 respectively, the inner ends of which telescope are keyed together for simultaneous rotation at 211. A set screw 212 normally prevents relative axial movement of the two hub members 209, 210, but loosening of this set screw will permit these members to be given a relative axial adjustment altho to a limited extent.

Radiating from the hub 209 are the spokes of a hand wheel 213 and radiating from the hub 210 are the spokes of a grooved pulley or sheave 214. The hand wheel and pulley or sheave are therefore nonrotatable relatively to each other, but both may be turned about the shaft 200, as will hereinafter be explained. Extending around the sheave and having one end fixed thereto is a rope or cable 215 which extends in a substantially horizontal direction and passes over a pulley 216. To the opposite end of this rope are secured weights 217. The constant natural

tendency of these weights is of course to unwind the rope from the grooved pulley, and to rotate the double hub member to which the pulley is connected on the shaft 200. The hand wheel 213 is however normally locked to the gear 205, one spoke of this hand wheel being provided with a shaft 217 upon which is fixed a pinion 218 normally in mesh with the teeth of gear 205 and shaft 217 having pivoted to its outer end a hand lever 219 which normally prevents rotation of shaft 217 in that its handle portion 220 projects through an aperture in the hand wheel and is prevented thereby from rotation about the axis of shaft 217. The hand wheel 213 and gear 205 being thus locked together against relative rotation the force transmitted by the cable 215 to the pulley is transmitted thru gear 205 to shaft 200 and as a result the pinions 202 have a constant tendency to walk along the racks 203 in the direction of the weight, thereby taking up slack in the two aprons which pass over the roller 112.

As the aprons lengthen in use this gradual movement of shaft 200 toward the left (Figure 25) will finally result in the lowering of the weights 217 until they rest upon the floor or base and it is quite apparent that when this occurs, forward movement of shaft 200 and further tensioning of the belt will not result. It is necessary, therefore, to provide means for shortening the effective length of the cable as the length of the aprons increases and I have provided means whereby this may be accomplished quickly and easily without stopping the operation of the machine. This means includes the mechanism hereinbefore described, and in particular the pinion 218 and the means for rotating the same, and a pawl or latch device generally indicated at P. It will be apparent that by swinging the hand lever 219 from its full line to its dotted line position in Figure 27, the operator may readily rotate shaft 217 and pinion 218 and thereby bring about relative rotation of gear 205 and hand wheel 213. In this relative rotation, the hand wheel 213 and the double hub member, together with the sheave 214, rotate about the shaft 200 with the result that the weights are lifted from the floor and brought to the proper elevation. When this operation has been completed the hand lever 219 is again slung downwardly to full line position (Figure 27) and the two relatively rotatable elements are again locked in their angular adjusted position.

For such adjustment as this, the pawl mechanism previously mentioned is unnecessary. It may sometimes happen however that it is desired to replace the cable 215 and, in order that this may be done without permitting the aprons to draw the shaft 200 too far to the right (Figure 25) and become wholly loose, and also when it is desired to move shaft 200 to the right (Figure 25) for

the purpose of loosening the aprons and to lock it in its adjusted position against the action of the weights 217, a pawl locking device now to be described is employed. By means of such pawl mechanism the shaft 200 may be locked against movement in either direction at any point of its possible travel along the racks 203. This pawl mechanism is illustrated clearly in Figures 28, 29 and 30. It comprises essentially a sleeve 221 rotatably mounted on the hub member 209 from which sleeve projects an arm 222. To the end of this arm is pivotally connected as at 223 an oscillatable lever 224 having an upper handle portion 225 and a lower bifurcated end below the pivot 223 which provides two spaced pawls or locking dogs 226. A lug 227 projecting laterally from the arm 222 into the space intermediate the dogs 226 comprises a stop which limits the rocking movement of lever 224 relatively to arm 222 and also serves to support one end of a coiled tension spring 228, the other end of which is connected at 229 to lever 224. This spring comprises a snap-over spring yieldably holding the lever 224 in either of its extreme positions of adjustment. The dogs 226 are adapted to alternatively engage the teeth formed on the upper edge of the longitudinally extending bar 207, previously referred to. When turned to the position shown in Figure 28 however neither pawl can engage the teeth of the rack and the shaft 200 is free to move in either direction. This is the normal position of lever 224.

It is quite apparent that by means of the pawl device just described, the shaft 200 can be positively prevented from moving in either direction. Thus the arm 222 may be rocked to either side of the vertical and the corresponding dog 226 engaged with the toothed rack with which it cooperates. If the weights are ineffective, the shaft may be locked against movement toward the right (Figure 25) under the pull of the aprons and, if it is desired to loosen the aprons, the shaft 200 may be moved to the right (Figure 25) by grasping and rotating the hand wheel 213 (without manipulating hand lever 219) and the shaft locked by the pawl mechanism. It will be noted from an inspection of Figure 30^a that a spring operated pawl 229' is pivotally supported upon one of the spokes of the hand wheel and normally engages the teeth of gear 205. As the hand wheel is caused to rotate relatively to the gear 205 due to the rotation of pinion 218, in the direction of the arrow, Figure 30^a, the pawl rides over the teeth of the gear and, when such relative rotation has been completed, locks the hand wheel and its associated elements in its annular adjusted position. This pawl may of course be manually released in the event that it is desired to lower the weights. In the normal operation of the machine, employing

as it does aprons of large size, for instance thirty or forty feet long and ten or twelve feet wide, it frequently happens that, due to various causes, one edge of the apron assumes a position slightly in advance of the other with its warp threads inclined instead of transverse to the machine. This may be brought about by inequalities in the texture of the apron, by slight inaccuracies in roller alignment or by the fact that a greater bulk of pieces is being ironed on one side of the machine than on the other. I have therefore provided means for compensating for such distortion of the apron and bringing about the proper alignment of the warp threads. This means comprises essentially the roller 122, shown in detail in Figures 31 and 32. This roller is a drive roller, being driven by a chain 231 from a sprocket 232 which is driven preferably from the main gear 27 thru suitable intermediate mechanism. The supporting shaft 233 of the roller is rotatably supported in eccentric bearings 234 and 235 respectively which bearings may be independently rotated by means of hand levers 236 and 237. It may readily be seen that by rotating either eccentric bearing in the aperture in the frame in which it is mounted, the axis of shaft 233 may be tilted so that the surface of one end of roller 122 is more remote from the surface of cylinder 16 than is the surface of the other end of this same roller. Such adjustments may be made from time to time as it becomes apparent that the apron has become distorted. Locking dogs 238 prevent rotation of the eccentric bearings 234 and 235 by engaging teeth formed on flanges 239 and 240 respectively, integral with the eccentric bearings, these dogs being of course lifted prior to manual adjustment of the bearings.

Immediately below the roller 122 and displaced laterally somewhat so as to be immediately above the common apron roller 111 is the second roller 123 and the apron associated with the second heated cylinder passes over and around the second roller after passing around the adjustable drive roller 122. Apron guide roll 123 is adjustable longitudinally of the machine, the bearings 243 upon which the ends of shaft 244 supporting this roller are mounted, having threaded engagement with longitudinally extending rods 245. Rotation of rods 245 of course results in adjustment of bearings 243 and of the axis of the roller. By adjusting this roller longitudinally of the machine the converging angle between the two aprons, just prior to the time when they come together in passing over roller 111, may be determined to suit the best operating conditions.

I have also provided means for effecting an adjustment of one of the tape supporting rollers so that the tension in the tapes may be maintained at any desired degree. This means is shown in Figures 33, 34 and 35. As

before explained rollers 186 and 187 are tape driving rollers, and are the only rollers employed in moving the endless tapes along their respective paths, the tapes being tightly gripped between the rollers just mentioned. They are drawn in the direction of the arrow (Figure 33) by the action of the rollers. At the uppermost points of travel the tapes pass over a guide bar 250 and at the rearmost point in their travel pass over and around a guide roller 251 rotatably mounted upon a transverse shaft 252. Shaft 252 has fixed thereon pinions 253 the teeth of which mesh with those of racks 254 supported in the frame. Rotatably mounted upon shaft 252 adjacent one of the pinions 253 is a pawl block 255 provided with two pawls indicated at 256 and 257 respectively. By rocking the block by means of a handle 258 either pawl may be brought into engagement with the teeth of rack 254. From the above it will be readily seen that by rotating the hand wheel 252 secured on the end of shaft 252, in a clockwise direction (Figure 33), the tension in the tapes may be increased since the pinions will tend to "walk" down the racks 254 carrying the shaft 252 and roller 251 with them. The pawl block may be adjusted so that pawl 257, by engaging the proper tooth of rack 254, prevents return movement of the shaft and roller.

When the frame F and rollers 186 and 187 are elevated by the mechanism previously described for the purpose of inspecting the doffing bar or loosening the apron, the tension in the tapes will be relieved and the shaft 252 will tend to move to the right (Figure 33), the pinions rolling down the racks 254. To prevent this the pawl block 255 may be tilted, prior to the elevation of frame F, so that the pawl 256 is in engagement with the rack. The shaft 252 and roller cannot therefore move under the influence of gravity during the raising and lowering of the frame F. As shown in the drawings, I have provided an adjustable stop indicated generally at 260 having upright arms 261 which lie on opposite sides of the shaft 252. All adjustments given the tapes are usually within a limited range, as thru a distance equal to that between the arms 261. If, due to stretching of the tapes it is desirable to move shaft 252 further to the right (Figure 33), the adjustable stop device 260 may be moved thru the desired distance by loosening the set screw 262 and, after adjustment, secured finally to the frame on which the rack is mounted, by again tightening the set screw.

A novel form of guard for the gearing described in detail in connection with Figures 23 and 24 is shown in Figure 36. The frame F is raised and lowered and the gears, by means of which rollers 104, 186 and 187 are driven, of course move with the frame. It is desirable to have these gears at all times pro-

ected by a guard to prevent injury to the operator of the machine. I have provided a guard, preferably formed of metal either by stamping or casting, which comprises an elongated member overlying the gears and with depending portions which lie along the sides of the gears, substantially as shown in Figure 36. This guard is pivoted to the frame at 265 and its forward end is connected by link 266 with the forward end of frame

F. As the frame F is elevated the guard is of course slightly lifted from the gear, but as the frame is again depressed into normal position the guard reassumes its first position. A somewhat similar guard is provided for the gearing at the opposite end of the machine, that is for the gearing provided for driving the adjustable drive roller 120. This roller is driven by a train of gears from the main gear 27, as shown in Figure 37. Inasmuch as the roller 120 may be manually adjusted by manipulating the hand wheel 267 (Figures 1 and 37) thru a worm and a worm wheel exactly in the same manner as in the case of roller 104, it is desirable that the

case of roller 104, it is desirable that the gears be protected by a swinging guard as in the former case. Such a guard is indicated at 268, being pivoted to the frame at 269 and fitting around the gears as closely as possible. The guard tilts with the gearing but upon return of the gearing to original position falls into its initial position. The projection 268' of the guard lies in the path of movement of one of the roller supporting arms and when the roller is raised this arm strikes the projection and lifts the guard. There is no link as in the case of the guard at the front of the machine.

The means for dislodging the work from the first apron at the point 116 (Figure 3) is shown in Figure 38. The roller 117 is shown to be provided with spiral ribs which diverge from a central point 271 toward both ends. These ribs cause the apron passing over the same to have an uneven surface, and the unevenness of the surface is constantly changing under the action of the ribs, resulting in complete dislodgment of the articles which might otherwise tend to adhere to the first apron and return to the first cylinder instead of being deposited upon the second apron to pass around the second cylinder. This roll is designated a worm-roll because of the spiral ribs but instead of these ribs I may substitute other devices by means of which the surface of the first apron is caused to become progressively uneven as it reaches the point 116.

The feed tapes 280 illustrated particularly in Figures 14 and 14^a, which pass over the feed board 69, are constrained to move in parallel paths. An angle bar 282 secured to the rear edge of the feed board is provided with downwardly projecting spaced guide fingers 283 the intermediate ones of which project

between the tapes respectively, and the two outer ones of which lie without the outer edges of the outer tapes. Each tape therefore runs between two guide fingers and is guided thereby, the fingers constraining the tapes to run in truly parallel paths. This means for guiding the tapes I have found to be eminently satisfactory in practice and an improvement upon prior devices heretofore suggested.

The design and arrangement of the component elements of the invention may, of course, be considerably varied to suit different working conditions and the invention is not limited to those details which have been set forth by way of example. It is apparent also that many of the novel features are adapted to be incorporated in machines of quite different type from that illustrated, for instance machines employing a single rotating drum and machines of the stationary heating chamber and traveling belt type.

Having thus described the invention, what is claimed as new and desired to be secured by Letters Patent is:

1. In an ironing machine of the class described, in combination, two spaced ironing cylinders, an apron associated with each of said cylinders, means for guiding said aprons in parallel substantially vertical paths between said cylinders, and a roller suspended in such manner as to swing toward and bear against one of said aprons under the influence of gravity, for the purpose set forth.

2. The combination set forth in claim 1 in which a weight connected to the roller is provided which becomes active to press the roller against the apron when the pressure of the roller tends to decrease due to its approach to the plane of its pivotal support.

3. In an ironing machine, in combination, two spaced ironing cylinders, an apron associated with each of said cylinders, said aprons cooperating in transporting the goods acted on by one cylinder to a point adjacent the second cylinder where they are separated, one apron passing around the second cylinder and the other returning toward the first cylinder, and means acting on said last mentioned apron adjacent the point of separation of said aprons, for causing dislodgment of any goods adhering thereto and their deposition on said second apron.

4. The combination set forth in claim 3 in which said last mentioned means comprises a worm roll.

5. The combination set forth in claim 3 in which said last mentioned means comprises a cylindrical roll having a surface provided with projections, for the purpose set forth.

6. In an ironing machine of the class described, having a heating chamber, an apron and a plurality of parallel spaced endless tapes cooperating with the apron, means for maintaining a desired degree of tension in

said tapes comprising a transverse member around which the tapes pass, and means for adjusting said member longitudinally of the tapes, said means including pinions on the 5 said member meshing with stationary racks, and a pawl for holding said member against movement longitudinally of the tapes in one direction.

7. In an ironing machine of the class described, having a heating chamber, an apron and a plurality of parallel spaced endless tapes cooperating with the apron, means for maintaining a desired degree of tension in said tapes comprising a transverse member 15 around which the tapes pass, means for adjusting said member longitudinally of the tapes, and a reversible pawl device to prevent movement of said member in either direction.

8. In an ironing machine of the class described, having a heating chamber, an apron and a plurality of parallel spaced endless tapes cooperating with the apron, means for maintaining a desired degree of tension in said tapes comprising a transverse member 25 around which the tapes pass, means for adjusting said member longitudinally of the tapes, adjustable limiting stops for determining the extent of movement of said member, a pawl mechanism for holding said member 30 against movement in either direction within the space determined by said stops.

9. In an ironing machine, in combination, a shaft from which the machine is driven, a constantly available power source for operating said shaft, means for engaging and disengaging the shaft and power source, operating mechanism for said means including a single element extending therefrom to the feed end of the machine, and manually operable and automatic devices respectively each adapted to cooperate with said element and whereby said element may be moved to stop the machine.

10. The combination with a power operated ironing machine, of a constantly available power source, a clutch device for connecting and disconnecting the power source from the machine, means for operating said clutch including a shaft extending from the 45 clutch to the feed end of the machine, and manual and automatic means for operating said shaft, both said means being normally positioned to cause engagement of said clutch, and being independently operable to 50 cause said clutch to disengage.

11. The combination with the power throw-off means of a power operated ironing machine, of an operating element therefor extending from the power throw off means to 60 the feed end of the machine, and a plurality of control members operably engaging the same, each of said control members being so connected to said operating element that it may operate the same without moving the 65 other members.

12. The combination with the power throw-off means of a power operated ironing machine, of an element operable to throw the power off or on, an automatic stop device connected to said element to operate the same 70 to cause the machine to stop, a manually operable starting and stopping member connected to said element, and a starting lever also connected to said element to move the same to starting position.

13. The combination with the power throw-off means of a power operated ironing machine, of an element operable to throw the power off or on, an automatic stop device connected to said element to operate the same 80 to cause the machine to stop, a lever also connected to said element for operating the same to cause the machine to start, and means associated with and operated by said lever for resetting the stop device.

14. The combination set forth in claim 13 in which the connection between said lever and element includes a lost motion device so arranged that the lever is not operated when the automatic stop device becomes operative 90 to stop the machine.

15. The combination with the power throwoff means of a power operated ironing machine, of a rotatable shaft connected to said means for operating the same, an automatic stop mechanism including a rotatable shaft, a manually operable member, and connections between said first mentioned rotatable shaft, the rotatable shaft of the stop mechanism, and said manually operable member, whereby said first mentioned shaft may be rotated in either direction by said member without interference with the rotatable shaft of the automatic mechanism.

16. In an ironing machine, in combination, a frame, a heated cylinder mounted for rotation in the frame, a doffing bar for removing the work from the cylinder, an apron, tapes cooperating with the apron to remove the work from the vicinity of the doffing bar, a plurality of rollers around which the tapes and apron, respectively, pass, adjustable arms upon which the rollers are rotatably supported, said arms being movable as a unit, and mechanical means for adjusting said arms so that all of the rollers may be simultaneously lifted away from the doffing bar.

17. The combination set forth in claim 16 in which the last mentioned means comprises a worm wheel connected to the arms and a worm rotatably mounted in the frame, together with a hand wheel for rotating the worm.

18. In an ironing machine, in combination, a frame, a heated chamber, an apron associated therewith, a roller over which the apron passes, adjustable arms upon which the roller is rotatably mounted, gearing for driving said roller mounted in part on one of said arms and in part on said frame, and a

guard for said gearing having a portion movable with said arms to all positions of adjustment thereof.

19. The combination set forth in claim 18 in which the guard comprises a housing which has one end pivotally connected to the frame.

20. The combination set forth in claim 18 in which the guard comprises an elongated housing having one end pivotally connected to the frame, and a link connecting a portion thereof remote from the pivotal point, to one of the adjustable arms.

21. In an ironing machine, in combination, a drum, an apron associated with said drum, a pressure roller, a member positioned adjacent the axis of the drum, and means connecting the roller and member whereby the roller may be yieldingly held against the apron or lifted out of contact therewith, said means including an extensible rod formed in two sections, the inner ends of said sections telescoping each other, one rod section being connected to the roller and the other to said member, an elongated spring having one end operatively connected to the inner end of one rod section and its opposite end to the inner end of the second rod section, the spring normally tending to draw the rod sections into telescoping relationship and to press the roller against the drum, and means for limiting the movement of the rod sections relatively to each other under the action of the spring whereby the roller may be moved entirely out of contact with the drum by adjustment of said member.

22. In an ironing machine, in combination, a drum, an apron associated with said drum, a pressure roller, a member positioned adjacent the axis of the drum, and means connecting the roller and member whereby the roller may be yieldingly held against the apron or lifted out of contact therewith, said means including an extensible rod formed in two sections, the inner ends of said sections telescoping each other, one rod section being connected to the roller and the other to said member an elongated helical spring encircling the telescoping inner ends of said rod sections, said spring having one end connected to the inner end of one rod section and its opposite end to the inner end of the second rod section, said spring being at all times under compression and normally tending to draw the rod sections into telescoping relationship and to press the roller against the drum, and means for limiting the movement of the rod sections relatively to each other under the action of the spring whereby the roller may be moved entirely out of contact with the drum by adjustment of said member.

In testimony whereof I hereunto affix my signature.

WILLIAM J. ASHER.
